UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE BAR

Application filed July 1, 1931. Serial No. 548,124.

This invention relates to grate bars of the heavy duty type and is concerned more particularly with a novel grate bar which comprises a carrier bar and a plurality of fuel supporting units or fingers removably mounted thereon. The new grate bar is especially adapted for use in locomotives, boiler furnaces, etc. and may be mounted in a frame or used as part of a traveling grate, as desired. For purposes of explanation, an embodiment of the invention suitable for use in a locomotive will be illustrated and described in detail.

The new grate bar comprises a carrier which includes a pair of spaced longitudinal supporting members and a plurality of fuel supporting units mounted on the members and having portions which extend down between the members and underlie the latter so as to secure the units against accidental displacement. Preferably each unit terminates at its lower end in a neck with a locking member, for example, in the form of a transverse end-piece, the length of which is greater than the distance between the two members of the carrier. At its ends, the carrier is provided with upstanding arms with trunnions and each arm has a passage formed through it wide enough to permit the end-pieces of the units to pass freely. By tilting the end unit of the carrier, that unit may be removed from the carrier with the end-piece on the neck of the unit moving through the passage in the trunnion arm, but when the unit is in normal upright position on the carrier, its end-piece underlies the carrier and prevents it from being thrown clear when the carrier is rocked to shake or dump the grate.

As another feature, the novel grate bar is constructed to give a wide opening during rocking to facilitate the passage of ashes to the ash-pan. For the purpose, the top surface of each member of the carrier is inclined to the horizontal with a downward inclination away from the longitudinal axis of the carrier. Each unit has correspondingly in-

clined surfaces resting on the supporting surfaces of the carrier and the units do not fit the carrier snugly but have a considerable freedom of angular movement relative to the carrier about the longitudinal axis of the latter. By reason of the formation of the supporting surfaces on the carrier as described, the rocking of the carrier during shaking causes each unit to continue its angular movement through an angle greater than that through which the carrier travels. The units consequently assume a more nearly vertical position than the top of the carrier, and the units on adjacent carriers in the grate provide a greater opening between them than they would if they were rigidly mounted on the carriers.

For a better understanding of these and other features of novelty in the new grate bar, reference may be made to the accompanying drawings, in which

Fig. 1 is a view in cross-section through a carrier showing one fuel-supporting unit in side elevation;

Figs. 2 and 3 are sectional views on the lines 2-2 and 3-3, respectively, of Fig. 1;

Fig. 4 is a view in side elevation of a portion of the carrier illustrating the manner in which the units are removed therefrom;

Fig. 5 is a view in side elevation of a portion of a carrier showing a pair of units in place thereon;

Fig. 6 is a plan view of a portion of a carrier with one unit in place thereon; and

Fig. 7 is a view similar to Fig. 1 showing the relative movement of the fuel-supporting units and carrier during rocking of the carrier.

Referring now to the drawings, the grate bar of the invention comprises a carrier which consists of a pair of longitudinal supporting members 10 spaced apart to form a slot 11 extending through the carrier from top to bottom and from end to end thereof. The supporting members 10 are connected at

their ends, for example, by upstanding arms 12 provided with trunnions 13 and, if desired, the members may be cross-connected at suitable points along their length by strengthening members, at least one strengthening member 14 being used and having a shaker arm 15 extending therefrom. The fuel-supporting units rest on supporting surfaces 16 on the members 10 and these surfaces are upwardly convergent as illustrated for a purpose presently to be described.

Mounted on the carrier are fuel-supporting units, one of which is illustrated in side elevation in Fig. 1. These units comprise a body 17 preferably in the shape of a plate provided on one or both sides with vertical lugs 18 spaced apart to provide air passages 19 for upwardly flow of air to the fuel resting on the unit. The lugs which lie at the middle of the unit and are designated 18a are not quite so thick as the others, and this facilitates mounting the unit on the carrier, as will presently be described. At the top, the unit is provided with a plurality of small projections 20 preferably arranged in groups of four, as illustrated in Fig. 6 with the units of each group separated by intersecting air channels 21, 22 and the groups of units separated by an air channel 23 which extends lengthwise of the unit. With this arrangement, air flowing up through the passages 19 and also between adjacent units on the carrier may flow across the top of the unit in the air channels 21, 22, 23 cooling the projections and affording a wide distribution of air to the fuel bed.

Formed on the under surface of each unit are spaced projections 24 having inclined seats 25 on their adjacent faces. These seats converge upwardly and their slope is similar to that of the supporting surfaces 16 on the carrier so that when a unit is in place on the carrier and the latter is in upright position, the units rest in upright position with their tops horizontal and with their seats in contact with the supporting surfaces on the spaced members of the carrier as illustrated in Fig. 1.

Extending downwardly from the under surface of each unit between the lugs 24 is a neck 26 terminating at its lower end in a transverse end-piece 27. The neck is considerably narrower than the width of the slot defined by the two supporting members 10 of the carrier and the neck is considerably longer than the depth of these members. The end-piece 27 is wider than the slot so that a unit cannot be lifted free of the carrier by a direct upward movement.

In order to provide for removal of the units, one or both of the arms 12 is cut away to form a passage 29 which is in communication with the end of the slot 11. This passage extends at an angle to the arm as shown

in Fig. 4. When the units are in normal upright position on the carrier as illustrated in Fig. 5, they are kept spaced apart a suitable distance by means of spacing projections 28 formed on certain of the lugs 18, and preferably there are two spacing projections on each face of a unit as shown in Fig. 1. The units of the group on the carrier are prevented from approaching each other too closely by means of the spacers but there is considerable play in the group and this is provided so that the units may be removed from the carrier.

In this operation, all of the units are moved close together toward one end of the carrier and the unit at the other end of the group is then tilted at an angle as shown in Fig. 4 until its end-piece 27 passes underneath the end of the arm 12 and into registry with the passage 29. The unit can now be moved free of the carrier with the end-piece moving through the passage. Since the middle lugs 18a on the units are not so thick as the others, they permit the use of a passage narrower in a direction lengthwise of the carrier than would be otherwise the case. These operations may be repeated until all or as many of the units as desired are removed. When the units are in their ordinary positions, the end units cannot be accidentally dislodged because the second unit from the end lies too close to the end unit to permit the latter to be tilted to the extent required to remove it. However, when all the units are moved manually toward one arm, the unit at the other end of the group is afforded sufficient space for removal in the manner described.

It will be observed that the neck and end-piece on each unit have a loose fit with the carrier and as a consequence, each unit has a considerable freedom of angular movement relative to the carrier about the longitudinal axis of the latter. This results in the units vibrating when the grate bar is installed in a structure, such as a locomotive, which is subject to shocks and jars, and, in addition, the angular movement relative to the carrier which is permitted to the units makes it possible to provide for a wide opening between adjacent grate bars when the bars are rocked. The wide opening effect is facilitated by making the supporting surfaces 16 on the carrier upwardly convergent.

The wide opening effect is illustrated in Fig. 7, in which the grate bar is shown in a position which may be considered to be that which it would occupy at the extreme end of its rocking movement during shaking. If the unit 17 shown in that figure were rigidly secured to the carrier, the unit would be tilted from the horizontal through an angle the same as that through which the carrier is rocked. However, when the carrier has been rocked through this angle, which, as shown,

is approximately 45° , it will be apparent that the seat 25a of the unit is supported by the surface 16a which has become substantially horizontal, but the surface 16b has assumed a substantially vertical position and offers no support to the seat 25a. As a consequence, when the carrier is rocked from the vertical to the angular position illustrated in Fig. 7, the removal of the support normally afforded by the surface 16b and the momentum of the unit results in the unit continuing its angular travel until it occupies the dotted line position in Fig. 7. In this position, one end 27a of the end-piece on the neck 26 engages beneath the supporting member 10a of the carrier and the unit is otherwise supported only by the extreme top edge of the surface 16b.

This additional movement of the unit through an angle greater than that passed through by the carrier produces a greater opening between adjacent grate bars for dumping than would be the case if the units were rigidly secured to the carrier. The extent of the opening between adjacent grate bars during shaking depends on the angle to which the units are inclined to the horizontal. If the units are rigid on the carrier and the latter is moved through an angle of 45° , the units will be similarly moved through an angle of 45° to the horizontal. In grate bars of this invention, however, the units travel through a greater angle than the carrier by reason of the loose mounting of the units on the carrier, and because of this greater displacement of the units from the horizontal, wider dump openings between adjacent grate bars are provided. In Fig. 7 it will be seen that the point 30 on the unit loosely mounted on the carrier is farther from the fuel-supporting unit on the adjacent grate bar than the corresponding point 31 on a rigidly mounted unit. Similarly, the point 32 on the loosely mounted unit is farther from the cross bar on the adjacent unit than the point 33 on the rigidly mounted unit.

By giving the units the freedom of angular movement relative to the carrier about the longitudinal axis of the latter, it is possible to obtain the wide dump openings and the provision of supporting surfaces on the carrier members 10 which are upwardly convergent as shown insures that the movement of the units relative the carrier will take place when the carrier is rocked.

The carrier and units of the new grate bar may be made of any suitable material and I contemplate making the carrier of cast iron or steel and the units either of cast metal or of sheet metal. Units of the latter construction are illustrated in my applications Serial Nos. 476,265, 546,778 and 546,779 filed August 19, 1930, June 25, 1931, and June 25, 1931, respectively.

I claim:

1. A grate bar which comprises the combination of a carrier made up of a pair of supporting members connected at their ends by arms and spaced apart to define an opening through the carrier from top to bottom and substantially the full length thereof, and a plurality of fuel-supporting units on the carrier, each having a part extending through said opening and provided with a portion underlying said members and of a greater over-all width than the width of the space between said members, at least one of said arms having a passage communicating with said opening and of a size to permit said portions of the units to be moved through it. 70

2. A grate bar which comprises the combination of a carrier made up of a pair of supporting members connected at their ends by arms and spaced apart to define an opening through the carrier from top to bottom and substantially the full length thereof, and a plurality of fuel-supporting units on the carrier, each having a part extending through said opening and provided with a portion underlying said members and of a greater over-all width than the width of the space between said members, 75 said part of each unit having a loose fit in the opening to allow the unit to have a limited freedom of movement relative to the carrier about the longitudinal axis of the latter and at least one of said arms having a passage communicating with said opening and of a size to permit said portions of the units to be moved through it. 80

3. A grate bar which comprises the combination of a carrier made up of a pair of supporting members connected at their ends by arms and spaced apart to define an opening through the carrier from top to bottom and substantially the full length thereof, and a plurality of fuel-supporting units on the carrier, each having a part extending through said opening and provided with a portion underlying said members and of a greater over-all width than the width of the space between said members, 85

said part of each unit having a loose fit in the opening to allow the unit to have a limited freedom of movement relative to the carrier about the longitudinal axis of the latter and at least one of said arms having a passage communicating with said opening and of a size to permit said portions of the units to be moved through it. 90

4. A grate bar which comprises the combination of a carrier made up of a pair of supporting members connected at their ends by arms and spaced apart to define an opening through the carrier from top to bottom and substantially the full length thereof, and a plurality of fuel-supporting units on the carrier, each having a part extending through said opening and provided with a portion underlying said members and of a greater over-all width than the width of the space between said members, 95

said part of each unit having a loose fit in the opening to allow the unit to have a limited freedom of movement relative to the carrier about the longitudinal axis of the latter with said movement limited by engagement of said portion of the unit with one of said members, and at least one of said arms having a passage through it communicating with said opening and of a size to permit said portions of the units to be moved through it. 100

5. A grate bar which comprises the combination of a carrier made up of a pair of supporting members connected at their ends by arms and spaced apart to define an open slot from end to end of the carrier, said members having supporting surfaces upwardly convergent, and a plurality of fuel-supporting units mounted on said surfaces, each unit 105

- having a part entering said slot and provided with a portion of greater over-all width than the width of the slot, said part having a loose fit in said slot to permit said unit to have an angular movement relative to said carrier about the longitudinal axis of the carrier, one of said arms having a passage through it communicating with said slot and of a size to permit said portion to be moved through it.
5. A grate bar which comprises the combination of a carrier made up of a pair of supporting members connected at their ends by arms and spaced apart to define an open slot from end to end of the carrier, one of said arms having a passage in it of greater width than the slot and communicating with the slot and said members having supporting surfaces upwardly convergent, and a plurality of fuel-supporting units having spaced 10 seats upwardly convergent and engaging the supporting surfaces on the carrier, each unit having a part entering said slot and provided with a portion of greater over-all width than the width of the slot, said part having a loose fit in said slot to permit said unit to have an angular movement relative to said carrier about the longitudinal axis of the carrier, the seats on said unit moving away from the supporting surfaces on the carrier 15 during said angular movement.
6. A grate bar which comprises the combination of a carrier made up of a pair of supporting members connected at their ends by arms and spaced apart to define an open slot through the carrier from end to end thereof, and a plurality of fuel-supporting units, each having a neck passing through said slot and terminating in a transverse end piece of greater length than the width of the slot and preventing free removal of said unit from the carrier, and a passage formed in at least one arm large enough to permit the end pieces on the units to pass therethrough.
- 20 7. A grate bar which comprises the combination of a carrier made up of a pair of supporting members connected at their ends by arms and spaced apart to define an open slot through the carrier from end to end thereof, and a plurality of fuel-supporting units, each having a neck passing through said slot and terminating in a transverse end piece of greater length than the width of the slot and preventing free removal of said unit from the carrier, and a passage formed in at least one arm and extending at an angle to the arm, said passage being large enough to permit the end pieces on the units to pass therethrough.
- 25 8. A grate bar which comprises the combination of a carrier made up of a pair of supporting members connected at their ends by arms and spaced apart to define an open slot through the carrier from end to end thereof, and a plurality of fuel-supporting units, each

having a neck passing through said slot and terminating in a transverse end piece of greater length than the width of the slot and preventing free removal of said unit from the carrier, the neck and end piece being proportioned to fit loosely in the slot to permit said unit to have an angular movement relative to said carrier about the longitudinal axis of the carrier, and a passage formed in at least one arm large enough to permit the end pieces on the units to pass therethrough.

9. A grate bar which comprises the combination of a carrier made up of a pair of supporting members connected at their ends by arms and spaced apart to define an open slot from end to end of the carrier, one of said arms having a passage through it of greater width than the slot and communicating with the slot and said members having supporting surfaces upwardly convergent, and a plurality of fuel-supporting units mounted on said surfaces and having spaced seats upwardly convergent, each unit having a neck passing through said slot and terminating in a transverse end piece of greater length than the width of the slot, said end piece preventing free removal of the unit from the carrier.

10. In a grate bar, a carrier comprising a pair of spaced supporting members defining a slot in the carrier extending from end to end thereof, and connections at the ends of said members, said members having supporting surfaces which are upwardly convergent, and at least one connection having a passage on it communicating with the slot and of greater width than the slot.

11. In a grate bar, a carrier comprising a pair of spaced supporting members defining a slot in the carrier and having supporting surfaces which converge upwardly, and arms connecting the ends of said members, each arm having a trunnion, and at least one of said arms having a passage in it communicating with said slot and of greater width than the slot.

12. In a grate bar, a carrier comprising a pair of spaced supporting members defining a slot in the carrier and having supporting surfaces which converge upwardly, and arms connecting the ends of said members, at least one arm having a passage through it communicating with said slot, said passage being wider than the slot.

13. In a grate bar, a carrier made up of a pair of supporting members connected at their ends and having top surfaces upwardly convergent, and a plurality of fuel-supporting units mounted on the carrier, each unit having a pair of pointed projections on its under surface, one side of each projection resting in contact with the top surface of one of said supporting members, said side being of less width than said surface, said members being spaced to define a slot and said units

each having an extension entering said slot and having a portion underlying parts of said members along the sides of said slot, said extensions fitting loosely within said slot to permit said units to have an angular movement relative to said carrier upon rocking of the latter, said unit swinging upon one or the other of its pointed projections as a pivot in said movement.

10 In testimony whereof I affix my signature.
JAMES S. THOMPSON.
